DRY PIPE VALVE

Willis K. Hodgman, Jr., Taunton, Mass.

Application August 25, 1934, Serial No. 741,382

3 Claims. (Cl. 169—22)

This invention relates to a dry pipe valve designed for supplying a system such as a fire prevention sprinkler system.

The object of the invention is to provide a construction which will prevent water columning taking place and thus the danger of the system becoming inoperative.

This and other objects and features of the invention will appear more fully from the accompanying description and drawing and will be particularly pointed out in the claims.

The drawing illustrates a dry pipe valve embodying a preferred form of the invention in which:

15. Fig. 1 is a vertical cross section taken on the line 1—1 of Fig. 2, and

Fig. 2 is a generally horizontal cross section taken on the line 2—2 of Fig. 1.

20. As the general construction, purpose and use of a dry pipe valve is well known and familiar, it is only necessary to describe in detail those features with which the present invention is particularly concerned.

The present invention is designed particularly 25 for embodiment in a dry pipe valve such as would be used in controlling the supply of water to the sprinkler heads in a fire prevention sprinkler system.

As illustrated, the construction comprises the 30 usual cast metal casing having the body portion 1 and the removable cover portion 2. At the bottom the casing is secured to the water system and the water passage 3 enters vertically at the bottom and terminates with the water valve seat or 35 port 4. At the top the casing is secured to the sprinkler system and the air pressure in the casing and in the sprinkler system is equalized through the passage 5.

The casing concentrically of the water valve 40 seat or port 4 for the water passage is provided with an upwardly extending projection 6 terminating in an air valve seat or port 7. Suitable clapper means including a water valve to cooperate with the water port and a peripherally 45 flexible air valve to cooperate with the air port are mounted in the casing to provide for the required movement of the two valves between closed and open position. Such clapper means may be of various construction within the scope 50 of the invention. As a simple and preferred form there is illustrated a swinging clapper pivotally mounted and carrying both the water valve to cooperate with the water port 4 and the air valve to cooperate with the air port 7.

55. The chamber 8 in the casing which is closed at the bottom by the air valve seating upon the air port 7 constitutes the air pressure chamber in which, under normal conditions, is maintained the necessary air pressure in the sprinkler system. An annular chamber 9 is formed between

the water port and the air port when the valves are closed and this chamber is normally open to the atmosphere through the radial opening 10 to which is connected the usual check valve controlled drip which of itself forms no part of the 5 present invention.

The clapper illustrated for closing the water port and the air port comprises a bifurcated arm 11 having an extended bearing 12 on a shaft 13 mounted horizontally in the casing. In the free 10 end of this arm is vertically and pivotally mounted the stem 14 of the clapper 15. This clapper is of metal and in the form shown is finished to provide a central water valve 16 to seat upon the water port 4 and concentric thereof the peripherally 15 flexible air valve 17 to seat upon the air port 7. The air valve is preferably formed as a flat annulus of rubber and is clamped to the body of the clapper 15 by means of the clamping ring 18 and the screws 19 which pass through the 20 clamping ring into the body of the clapper. It will thus be seen that this construction presents a swinging clapper having the central water valve 16 to seat and close upon the water port 4 and the peripherally flexible air valve 17 to seat upon and 25 close upon the air port 7.

Under normal conditions the sprinkler system, and consequently the air chamber 8 in the casing of the dry pipe valve, is filled with air under pressure and this pressure exerted upon the relatively 30 large area of the clapper opposite the air port is sufficient to hold the clapper with the valves seated against the pressure of the water upon the relatively smaller area of the clapper 35 opposite the water port.

In the case of a dry pipe sprinkler system, when a fire occurs and one or more sprinkler heads are opened, the pressure in the air chamber 8 is rapidly reduced well below that sufficient to hold the clapper means closed and consequently the 40 clapper means is moved open and the water enters the system.

In order to prevent the clapper means from returning to closed position, various constructions may be employed. For this purpose in the 45 form of clapper means illustrated the clapper 15 is shown provided near its periphery at one side with a recess filled with lead 20 and the clamping ring 18 is provided with a depending projection 21. In normal position the projection 50 21 is at one side of a rib 22 on the casing. When the clapper 15 has been swung open by the inrush of water through the dry pipe valve, the weight 20 causes the clapper to rotate at its stem 14 in the arm 11 and the proportions are such 55 that when this takes place, the projection 21 is brought into such position that if the clapper should drop, the projection would rest on top of the rib 22 and thus prevent the clapper from moving to closed position.

- But, when for any reason there has been a gradual reduction in the air pressure in the system and consequently in the air chamber 8, a point may be reached where the clapper means is 5 very evenly balanced between the air and water pressures and practically floats on the water so that slight amounts of water flow or surge past the water and air valves into the air chamber. This condition may continue sufficiently to cause 10 "water columning", that is, enough water may work past the valves gradually to form a sufficient head on top of the air valve to hold both valves closed against the water pressure and thus render it possible for the entire device to be 15 inoperative.
- The object of the invention is to prevent any such water columning taking place as the result of a continuing flow or surge of water into the air chamber.
- 20 For this purpose in the preferred construction illustrated a latch member 23 is pivoted at 24 on a projection 25 extending inwardly from the cover 2 of the casing and is provided with a stop 26 limiting its downward movement. This 25 latch cooperates with a shoulder 27 formed on one of the bifurcations of the arm 11 of the clapper 15. The latch and projection 27 are so positioned that if the clapper is opened slightly, the latch will drop over the shoulder 27 and lock 30 the clapper against closing. But it will be remembered that the air valve 17 is a flexible member and is made flexible in order to ensure both air and water valves seating firmly under normal conditions. Consequently the latching construction, such as the latch 23 and cooperating shoulder 27, must be so positioned as to lock the clapper sufficiently wide open so that the flexible air valve 17 cannot be forced or bent down on to the air valve seat 1. But in order to swing the 40 clapper to such a position where it is latched or locked with the flexible air valve out of reach of its seat, a greater force is required than that resulting from the small flows or surges which are the cause of the difficulty to be overcome.
- 45 The present invention provides means for resisting a surge of water past the clapper means by a direct path into the air chamber and thus augmenting the movement of the clapper means sufficiently to ensure the locking of the clapper 50 means by the latch or locking means. In the construction of pivoted clapper carrying both valves as illustrated this is secured by forming or providing on the clamping ring 18 a baffle flange 28 depending from the clapper interiorly concentric with and quite closely adjacent the air port 1. This baffle flange, as shown in Fig. 2, 55 extends well around the portion of the clapper opposite its pivot and there is thus formed a narrow, vertical, annular passage 29 between the air port 1 and the projection 28. Consequently any slight flow or surge of water past the water valve 16 and the water port 4, which tends to move in a direct path from the top of the water port to the top of the air port is instead at first 60 deflected downward in the chamber 9 around the bottom edge of the projection 28 and up between this projection and the air port through the space 29. This resistance to the normal or direct path of flow causes the clapper to rise until 65 the path of flow approaches the normal direct path and thus when the pressure is sufficient to force the clapper open, the swing of the clapper is augmented sufficiently to ensure the engagement of the latch 23 with the shoulder 27.

The invention thus ensures that any flow or surge of water past the air valve into the air chamber sufficient to start water columning is also sufficiently augmented in force by the means of this invention to move the clapper means into such position that it is locked with the periphery 5 flexible air valve in such a position that it cannot be forced into engagement with and close the air port.

Having thus described the invention, what is 10 claimed as new, and desired to be secured by Letters Patent, is:

1. A dry pipe valve comprising a casing, an air pressure chamber in the casing, a water passage having a port opening into the air chamber, 15 an air port in the casing surrounding the water port, a chamber in the casing between the air and water ports normally open to the atmosphere, movable clapper means having a water valve to seat upon and close the water port and a peripherally flexible air valve to seat upon and close the air port, means cooperating with the clapper means when moved open slightly by a surge of water to lock the clapper means in a position such that the flexible periphery of the air valve 25 cannot be forced into engagement with and close the air port, and means on the clapper means acting to resist a surge of water by a direct path into the air chamber and thus augment the movement of the clapper means by said 30 surge sufficiently to ensure the said locking of the clapper means by the locking means.

2. A dry pipe valve comprising a casing, an air pressure chamber in the casing, a water passage having a port opening into the air chamber, 35 an air port in the casing surrounding the water port, a chamber in the casing between the air and water ports normally open to the atmosphere, movable clapper means having a water valve to seat upon and close the water port and a peripherally flexible air valve to seat upon and close the air port, means cooperating with the clapper means when moved open slightly by a surge of water to lock the clapper means in a position such that the flexible periphery of the air valve 40 cannot be forced into engagement with and close the air port, and means on the clapper means acting to deflect from a direct path between the water and air ports a surge of water into the air chamber and thus augment the movement of the clapper by said surge sufficiently to ensure the said locking of the clapper means by the locking means.

3. A dry pipe valve comprising a casing, an air pressure chamber in the casing, a water passage having a port opening into the air chamber, 55 an air port in the casing surrounding the water port, a chamber in the casing between the air and water ports normally open to the atmosphere, a swinging clapper having a central water 60 valve to seat upon and close the water port and a peripherally flexible air valve to seat upon and close the air port, a latch acting to engage the clapper when swung open slightly by a surge of water and lock it in a position such that the flexible periphery of the air valve cannot be forced into engagement with and close the air port, and a baffle flange depending from the clapper interiorly concentric with and adjacent the air port acting to resist a surge of water by a direct path into the air chamber and thus augment the swing of the clapper by said surge sufficiently to ensure its engagement with the latch.
